UNITED STATES PATENT OFFICE

EDWARD B. DENNIE, OF ROCHESTER, NEW YORK, ASSIGNOR TO DECO ENGINEERING CORPORATION, OF LAS VEGAS, NEVADA, A CORPORATION OF NEVADA

BEATER FOR TEXTILE FLOOR COVERINGS, SUCH AS RUGS AND CARPETS

Application filed January 14, 1927. Serial No. 161,079.

The present invention relates to beaters for textile floor coverings such as rugs and carpets and an object thereof is to provide a construction in which the dust or dirt removed from the floor covering is collected in such a manner as to prevent its passing into the room in which the machine is situated. Another object of the invention is to utilize a suitable spray to draw the dust or dirt from a floor covering which is being subjected to a beating action so that the dust also may be saturated by the spray and collect in a suitable liquid container. Still another object of the invention is to create a draft through the floor covering while the beating thereof is taking place, saturate the dust in the dust laden air with a suitable spray, and conduct the saturated dust against the surface of liquid in a container from which the air is permitted to pass off, leaving the dust in the liquid of the container.

To these and other ends, the invention consists of certain parts and combinations of parts, all of which will be hereinafter described, the novel features being pointed out in the appended claims.

In the drawings:

Fig. 1 shows the front elevation of a machine constructed in accordance with this invention;

Fig. 2 is a side elevation;

Fig. 3 is a vertical section on the line 3—3, Fig. 4; and

Fig. 4 is a transverse section through the machine.

Referring more particularly to the illustrated embodiment of the invention, 1 indicates the side frames of the machines which are connected by a perforated bed plate or work support 2 over which the floor covering 3 is moved in any suitable manner as by a roller 4. The side frames of the machine project upwardly above the bed plate or work support 2 and extend to the rear of said bed plate or work support. A cross bar or hinge piece 5 connects the side pieces in rear of and in spaced relation to the bed plate or work support 2 and a hinged cover 6 turns on this cross bar or hinge piece 5 and provides a chamber 7 above the bed plate or work sup-

port 2 having an entrance opening 8 in advance of the roller for the floor covering 3 and providing a wide throat 9 between the work support 2 and the cross bar 5 through which the floor covering may be discharged and through which air may enter the hood or chamber as will be described.

Journalled in the side frames is a shaft 10 to which beater straps 11 are secured in any suitable manner, the shaft being situated in a vertical plane to one side of the work support 2 and being also situated in a horizontal plane above the work support 2. With the rotation of the shaft 10, the straps 11 will impinge upon the floor covering 3 on the work support 2, and subject the floor covering to a beating action. At the same time, the straps by working in an enclosed hood or casing formed between the side walls and the cover 6 draw air into the casing through the inlet 9 and this air is directed in a downward direction through the floor covering and the perforated table. The shaft 10, in this instance has a gear wheel 12 thereon meshing with a large gear wheel 13 on the shaft of the roller 4 so that the two shafts will turn together, the beater at a higher speed than the roller.

The dust passing through the perforated work support 2 is directed into a chamber 80 or conductor 14 which depends from the table 2 and collects all the dirt or dust and air passing through the perforated table and floor covering. This conductor becomes restricted gradually toward its lower or discharge end which is situated in a liquid receptacle 15 supported by and between the side frames of the machine beneath the table 2. The lower end of the conductor is below the upper edges of the receptacle 15 so that all materials passing from the conductor will strike against the liquid 16 in the receptacle 15, and the air will then pass upwardly from the liquid and issue from the top of the receptacle free from dust. An outlet 19 may lead the dust and water from the receptacle to a sewer or other outlet.

With the end in view of insuring the elimination of the dust and at the same time creating greater suction through the floor cover-

ing, a means is provided which creates a spray of water or the like within the conductor so that the dust laden air passing through the conductor strikes this spray which moistens the dust and insures its being held by the liquid in the container 15. At the same time, the spray acts as an ejector and assists in creating a draft through the perforated work support and the floor covering. This means, in this instance, comprises a supply tube 17 extending between the side frames 1 and having lateral nozzles 18 depending therefrom in the conductor 14.

In the operation of the invention, the rug 3 is placed on the work support 2 and fed beneath the roller 4 which carries said rug into the machine, over the perforated portion of the work support. While travelling on the work support the beater straps 11 strike the upper surface of the rug and at the same time cooperate with the walls of the housing cover 6 to create a current of air through the housing by way of the inlet at the rear of the machine, this air passing through that portion of the rug travelling over the work support and carrying the dust into the conduit or conductor 14 where the spray producing acts on the dust laden air creating a still further draft and depositing moistened dust in the receptacle 15 from which it passes by way of the outlet 19.

From the foregoing it will be seen that there has been provided a cleaner for textile floor coverings in which the dust laden air from the floor covering is directed to a liquid container which collects the dust from the air and permits the air to issue from the machine free from dust. Provision is made for saturating the dust laden air with moisture before the dust laden air strikes the liquid in the container. This result is secured by a spray filling the conductor between the rug and the liquid receptacle in such a manner as also to create a suction through the floor covering.

What I claim as my invention and desire to secure by Letters Patent is:

1. A beater comprising a work support over which the material to be beaten is fed at one side, said support having openings through which the dust passes, a rotary beater having a shaft and flexible beater members, the shaft being situated above and at that side of the support opposite the side at which the material is fed to the support, a housing for the beater and the work support having an air inlet opening lying beneath the beater and on that side of the work support opposite the side to which the material is fed thereto and through which the material, after passing over the work support, may be discharged, said housing having a curved portion arranged adjacent the beater and concentric therewith and extending substantially from the air inlet to the work support to

cause the beater when traveling by said curved portion to create a draft through the inlet and through the openings of the work support, and means for rotating the beater in a direction to cause its flexible beater members to travel first past the inlet opening, thence upwardly, forwardly and downwardly to strike the material on the work support.

2. A beater comprising a work support having openings, a beating mechanism operating on one side of the work support to cooperate with the work on the support, a spray producing means arranged on the opposite side of the work support to saturate the dust laden air passing through the openings of the work support, the spray from the spray producing means being directed away from the work support, and means surrounding the spray producing means to cause the spray to create a draft through the work support.

3. In a beater, the combination with a work support provided with openings, of a conduit depending from the work support, a liquid receptacle provided with an overflow and arranged beneath said conduit with the end of the conduit spaced from the overflow level of the receptacle, and spray producing means arranged in said conduit and having its spray directed toward the lower end of said conduit.

4. A beater comprising a horizontal work support provided with openings, a beating mechanism arranged to operate on the upper side of the work support and to beat the work thereon, means depending from the lower side of the work support and forming a conduit having a discharge at its lower end, a receptacle for containing a liquid against which the dust from the conduit is discharged, the upper edge of said receptacle being above the discharge opening of the conduit, and spray producing means arranged in said conduit beneath the work support and above the discharge opening, said spray producing means discharging downwardly in the conduit to create a draft therein through the openings of the work support.

5. A beater comprising a work support provided with openings, a beater mechanism operating on one side of the work support, and spray producing means arranged on and in proximity to the other side of the support and directed away from the support and a conduit arranged about the spray producing means and having a draft created therethrough by the spray producing means to carry the dust away from the work support.

6. A beater comprising a work support provided with openings, a heater mechanism operating on one side of the work support, a spray producing means arranged on and in proximity to the other side of the support

and directed away from the support, a conduit arranged about the spray producing means and having a draft created there-through by the spray producing means to carry the dust away from the work support, and a liquid holding receptacle into which said spray discharges.

EDWARD B. DENNIE.
